UNITED STATES PATENT OFFICE.

GEORGE MADDEN AND LUTHER MADDEN, OF KENT, IOWA.

CRUDE-OIL BURNER FOR STOVES.

No. 884,939.

Specification of Letters Patent.

Patented April 14, 1908.

Application filed February 25, 1907. Serial No. 359,078.

To all whom it may concern:

Be it known that we, GEORGE MADDEN and LUTHER MADDEN, citizens of the United States, residing at Kent, in the county of Union and State of Iowa, have invented a certain new and useful Crude-Oil Burner for Stoves, of which the following is a specification.

The object of our invention is to provide a device to be used in the nature of an attachment for conveniently using crude oil as a fuel in an ordinary stove.

More specifically it is our object to provide an attachment of this kind in which the oil receptacle may be readily, quickly and easily detached for purposes of refilling, and dripping or leakage of the crude oil be prevented when the receptacle is being removed.

Our invention consists in the construction, arrangement and combination of the various parts of the device, whereby the objects contemplated are attained, as hereinafter more fully set forth, pointed out in our claims, and illustrated in the accompanying drawings, in

which—

Figure 1 shows a perspective view of a stove having our improvement applied thereto as in practical use. Fig. 2 shows an enlarged, detail, sectional view of the coupling device and funnel for connecting the receptacle with the feed pipe. Fig. 3 shows a detail, sectional view illustrating the combustion pan within the fire-box of the stove, and Fig. 4 shows a detail view of one of the feed pipe supporting brackets.

Referring to the accompanying drawings, we have used the reference numeral 10 to indicate the stove having a fire-box 11. The stove is of the ordinary construction and forms no part of our present invention.

The combustion pan comprises a shallow rectangular receptacle 12 with an open top. Connected with the receptacle are two hangers 13 to pass under the receptacle and extend over the fire-box 11 of the stove, thus supporting the pan near the top of the fire-box.

The means for supplying crude oil to the pan comprises a standard 14 mounted on the stove and having an oil receptacle 15 detachably mounted thereon. A discharge pipe 16 leads from the oil receptacle and is provided with a globe valve 17 of ordinary construction. Beyond the valve the pipe 16 extends downwardly at 18 and its lower end is screw-threaded at 19.

The reference numeral 20 indicates a funnel having a screw-threaded plug 21 in its bottom provided with a screw-threaded opening to receive the part 19. A pipe 22 is provided having at its upper end a screw-threaded portion 23 designed to enter the opening in the plug 21, the screw threads thereon being arranged at the same angle as the screw threads on the part 19. By this arrangement, the funnel 20 may be turned and the plug 21 will move downwardly until the upper pipe which is attached to the receptacle is released from the plug. The said pipe 22 is supported by suitable brackets, herein-after described. Each bracket comprises a body portion 24 with two parallel projections 25 designed to admit the flange of a stove top between. A set screw 26 is placed in one of the parts 25 by which it may be secured to the stove flange. The bracket is also provided with a loop or ring 27 through which the pipe 22 is extended and this loop or ring is provided with a set screw 28 by which the pipe may be secured in position. The feed pipe 22 is also provided with a globe valve 29 near its discharge end and the end of the pipe is designed to project into an opening formed for it in the top of the stove so that it will discharge into the central portion of the pan 12.

In practical use, it is obvious that the device may be quickly and easily applied to a stove of any ordinary type. The valve 17 is normally left open and the supply of oil is controlled by the valve 29. The oil flows into the central portion of the pan 12 and spreads within the pan and when ignited will burn and the heat arising from the fire will be applied directly to the top of the stove. Assuming that it is desired to refill the tank 15, the operator first closes the valve 17 and then turns the funnel 20 until the screw-threaded portion 19 is free from the plug 21. Then if there is any dripping from the pipe, it will drop into the funnel. After the pipe has ceased dripping the tank 15 may be removed to a convenient place for refilling and after it is placed in position, the funnel 20 may again be screwed to the part 19 and the valve 17 opened and the device ready for use.

Having thus described our invention, what we claim and desire to secure by Letters Patent of the United States, therefor is—

1. In a device of the class described, the combination of a receptacle, a discharge pipe for the receptacle having a screw-threaded

end, a fuel feed pipe having a screw-threaded end and a funnel having a plug provided with a screw-threaded opening designed to receive both of said screw-threaded pipes and 5 when turned in one direction to release the discharge pipe of the receptacle and permit the pipe to drain into the funnel.

2. In a device of the class described, the combination of a standard, a supply tank 10 detachably mounted on the standard, a discharge pipe for the supply tank having a screw-threaded downwardly projected end, a valve in the pipe, a fuel feed pipe having its upper end screw-threaded, a funnel, a plug

in the funnel having a screw-threaded opening, 15 said plug having both of said screw-threaded pipes admitted into it, said parts so arranged that by turning the funnel in one direction, the upper pipe may be removed from the plug and be permitted to drain into the 20 funnel.

Des Moines, Iowa, February 7, 1907

GEORGE MADDEN.
LUTHER MADDEN.
